Primary Examiner — Jonathan J Han*(74) Attorney, Agent, or Firm* — Hartman Global IP Law; Gary M. Hartman; Domenica N. S. Hartman(57) **CLAIM**

The ornamental design for a shoe upper, as shown and described.

DESCRIPTION

FIG. 1 is a top, front, and right side perspective view of a shoe upper in accordance with this invention.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof;

FIG. 8 is a bottom, rear, and left side perspective view thereof.

The broken lines in the drawings show portions of the shoe upper and environmental structure of the sole that form no part of the claimed design.

1 Claim, 7 Drawing Sheets(56)
